FREDRIK LJUNGSTRÖM, OF LIDINGÖ-BREVIK, AND ISIDOR BROBERG, OF SKARSATRA, SWEDEN, ASSIGNEES TO AKTIEBOLAGET LJUNGSTRÖMS ANGTURBIN, OF STOCKHOLM, SWEDEN, A CORPORATION.

AIR-COOLED CONDENSER.

Application filed April 13, 1922, Serial No. 552,410, and in Sweden November 8, 1921.

Heretofore, air-cooled condensers have been proposed, wherein steam to be condensed is conducted through a steam pipe from which smaller cooling elements in the form of pipes, bent disks or the like project in such a manner as to permit an air current to pass between them. To these cooling elements there is connected the steam supply pipe with an outlet pipe for water, air and noncondensed steam. Preferably, this outlet pipe has served as a supply pipe for another group of cooling elements, whereby the whole air-cooled condenser is divided into two or more groups connected in series. In each of such groups the steam supply is common for all cooling elements, independent of the cooling capacity of each cooling element. If such a condenser is placed in the open air and the external temperature is low, cases may occur when, for example, a greater cooling capacity is imparted to one cooling element than to the others by the air surrounding the condenser. In such cases the steam entering the said cooling element is condensed quicker than in the other elements, without the condensed steam being replaced by a sufficient amount of fresh steam, by reason of which the element will for a great part contain moist air, the moisture of which will freeze to ice in case the temperature is below zero and may entirely stop up the passage of the cooling element, thereby incapacitating the element with the danger of its freezing and bursting.

The present invention relates to an air-cooled condenser comprising groups of cooling elements, the said elements being placed side by side and connected to manifolds, each of which serves as the outlet of one group and the inlet of the next group, the outlet end of each element being throttled to a smaller cross-section than its inlet end. With this arrangement the fall of pressure between the outlet end of the element and the manifold into which it discharges is so great that an outflow from the element is always obtained, even when the cooling effect is not uniform.

In the accompanying drawing which illustrates the invention Fig. I shows diagrammatically an embodiment of a condenser according to the invention and Fig. II shows a diagram of the falls of pressure

in the same. Figs. III, IV, V and VI illustrate different details.

Fig. I shows a condenser in which the elements 11 are divided into groups 1, 2, 3, connected in series, so that the steam passing group 3 has already passed through group 1 and then through group 2. 4 denotes the inlet pipe of the whole condenser and 5 the outlet pipe thereof leading to an air pump. Pipe 6 is the outlet pipe or manifold of group 1 and the inlet pipe of group 2, while pipe 7 is the outlet pipe of group 2 and the inlet pipe of group 3. From the manifolds 6, 7 and 5, the condensate water is drawn off through the pipes 8, 9 and 10. In a condenser without the above-mentioned subdivision in groups, the manifold 6 is connected directly to the air-pump, groups 2 and 3 being omitted.

The diagram disclosed in Fig. II shows the falls of pressure in the condenser shown in Fig. I, the ordinates representing the pressure and the abscissas the distances of the points in question from the supply pipe 4. Supposing a pressure of P prevails in said pipe 4 corresponding to the point 12 in the diagram, then in a condenser of the type heretofore known the fall of pressure P_0 designated for the whole condenser is divided for instance into a fall of pressure P_1 in the first group, a fall of pressure P_2 in the second group and a fall of pressure P_3 in the third group, the pressure of the different groups falling according to the curves 21, 23 and 24 respectively.

If now for some reason or other the tube group 11^a has exercised an increased activity for some time, then all the steam may be condensed for instance at 11^b. On account of this condensation nearly the whole fall of pressure P_1 intended for said group has occurred, and the pressure in the remaining part of the group will hardly surpass the pressure of the pipe 6. The remaining fall of pressure P_x is not sufficient to exhaust the moist air from the element, and consequently said air will remain in this part of the element where the formation of ice may cause bursting of the element.

In the embodiment of the present invention as shown in Fig. I the outlet of each cooling element is markedly reduced. This result is obtained by arranging a throttling

disk 11^d at the outlet end. Hereby the pressure conditions in the condenser will be altered. The fall of pressure P_o for the whole condenser will be divided into P_{11} for the 5 elements of the first group, P_{21} for the elements of the second group and P_{31} for the elements of the third group. In the elements of the first group the pressure falls according to the curve 22 to the point 15 immediately before the throttling disks 11^d, and then a marked fall of pressure will occur, the line 16 representing the fall to the pressure of the pipe 6. In the elements of the second and third groups which are also provided with 15 throttling disks the falls of pressure will follow the curves 26 and 27 respectively, abrupt falls of pressure arising at the outlet openings. The fall of pressure P_o available for the whole condenser is not surpassed. In 20 the embodiment shown, by reason of the fact that the elements of a following group 2 and 3 have greater passage areas than those of a preceding group 1 and 2, thus causing a decrease of the resistance in same so that consequently the steam requires a smaller fall of 25 pressure for passing through same.

If the elements of the second group are not provided with any throttling disks but have greater passage areas than those of the first 30 group, the pressure will fall according to the curve 25, the fall of pressure P_4 at disposal for the first two groups being not surpassed.

It is evident that should the condenser consist of only one group of elements, the increased fall of pressure necessary on account of the throttling of the elements may be obtained in any manner, as for instance by introducing the steam in the elements at a 40 higher pressure than before or by maintaining a lower vacuum in the condenser. These measures may also be taken in case of the condenser consisting of several groups connected in series, the increase of the cross-section of the elements of a following group 45 in relation to a preceding group may then be dispensed with.

In order to obtain a throttling action of the elements, throttling disks may be used, as 50 mentioned above, at the outlet of the element. Instead thereof the cross-section of the elements from the inlet end to the outlet end may also be continually decreased, which in certain cases may be more advantageous than the use of throttling disks partly from a manufacturing point of view and partly from consideration of space. If the elements consist in known manner of flattened pipes, the height h at the inlet side A of such a 55 pipe may thus be reduced along the whole length of the pipe to a height h^1 at the outlet-end B, the outlet area at B being then also smaller than the inlet area at A. According to Fig. IV, the thickness b of the element 60 may be continually decreased in the same

manner, thus producing a passage area which is contractive toward the end of the outlet.

If in known manner several elements 31 are inserted in a common collecting pipe 32, as indicated in Fig. V, throttling may be obtained for the whole of this combination of cooling elements in the collecting pipe 32 by the insertion of a throttling disk 36 into the lower narrower extension of the collecting pipe 32, or by the reduction of this pipe, as 75 shown at 37.

Then it may also happen that a cooling element in this combination, compared with the other cooling elements in the same combination, may produce a greater cooling effect, 80 the said cooling element having then, preferably, to be throttled independently of the remaining cooling elements. This is preferably attained by the element being flattened so that the element changes its cross-sectional appearance from the full lines to the dash-lines, as shown in Fig. VI at 33. Furthermore, a whole disk with narrow openings or small apertures may be placed in front of the mouths, as shown at 34.

When, as shown in Fig. V, several elements in each group are inserted in a common collecting pipe, such an arrangement may also be applied to Fig. I, as in this case the elements 11 shown in this figure represent each such an under-group, comprising for instance four or five elements 31 and the corresponding collecting pipe 32.

Having now particularly described and ascertained the nature of the said invention and in what manner the same is to be performed, we declare that what we claim is:

1. An air cooled condenser comprising groups of cooling elements, the elements of each group being placed side by side, said groups being connected in series, and throttling means between one group and the following.

2. An air cooled condenser, comprising a plurality of groups of cooling elements, the elements of each group being placed side by side and having inlets and reduced outlets, said groups being connected in series.

3. An air cooled condenser, comprising a plurality of groups of cooling elements, the elements of each group being placed side by side, said groups being connected in series, each element of a following series having a larger passage area than each element of a previous series.

4. An air cooled condenser, comprising a plurality of cooling elements, the elements of each group being placed side by side and having inlets and reduced outlets, said groups being connected in series, each element of a following group having a larger passage area than each element of a previous series.

5. An air cooled condenser, comprising a plurality of groups of cooling elements, the elements of each group being placed side by side

side and divided into several under-groups each comprising a number of cooling elements, said under-groups being connected in parallel, whereas said groups are connected in series, and throttling means between one group and the following.

6. An air cooled condenser, comprising a plurality of groups of cooling elements, the elements of each group being placed side by side and divided into several under-groups, each comprising a number of cooling ele-

ments, a collecting pipe common to all elements of each under-group, said groups being connected in series, whereas the under-groups of each group are connected in parallel, and a throttling member in the outlet of each collecting pipe. 15

In testimony whereof we affix our signatures.
